UNITED STATES PATENT OFFICE.

CHARLES LIONEL MARCUS, OF NEW YORK, N. Y.

VANITY CASE.

Application filed December 1, 1923. Serial No. 677,931.

This invention relates to vanity cases. Among the objects of this invention is to provide a vanity case of the character described which shall be capable of neatly holding a plurality of toilet articles including a face powder, and having means for shielding the powder from dirt and other foreign matter.

Other objects of this invention will in part be obvious and in part hereinafter pointed out.

Certain features herein shown and described are shown, described and claimed in my copending application Serial No. 625,902 filed in the United States Patent Office on the 17th day of March, 1923 and accordingly are not claimed herein.

With the above exception, the invention accordingly consists in the features of construction, combinations of elements and arrangement of parts which will be exemplified in the construction hereinafter described and of which the scope of application will be indicated in the following claim.

In the accompanying drawing in which is shown one of the various possible illustrative embodiments of this invention,

Fig. 1 is a perspective view of a vanity case embodying the invention shown in open position; and

Fig. 2 is a longitudinal cross-sectional view of the embodiment shown in Fig. 1 when closed.

Referring in detail to the drawing, the vanity case there shown is seen to comprise a container 10 of suitable shape, such as a heart-shape or the like ornamental configuration. Hinged to the container as at 11 is a cover 12 similar in shape to the container 10 and adapted to close the same with the lower edge 13 of the cover flush with the top edge of the container. A mirror 14 is provided on the interior face of the cover 12, being secured in any suitable manner, such for example as by means of the metal frame 15.

The container and cover may each be made in one piece by shaping them out of metal or the like material so as to provide the shaped shell member 10^a, 12^a for the container and cover respectively. Each of these members may be suitably lined or covered with a suitable material, such as leather or the like, as shown at 10^b, 12^b, respectively. A similar lining 10^c may be provided for the bottom of the container and the material

thereof, if desired, made to extend as at 11^a over the hinge 11 to completely conceal the latter from view.

The container 10 is divided into two separate compartments, 16, 17 by means of a shaped insert comprising a hollow member made of celluloid or the like material having a main body portion 16 shaped so as to conform to the interior contour of the container with the edge of said body portion fitting snugly against the interior wall 16^a of the container, and being of such height as to extend down to the bottom of the container and a little above the top edge 14^a thereof, as at 16^b, so that when the cover is closed on the container, the former fits over said extended portion 16^b, as will be clear from Fig. 2. Adjacent the rear of the container, the insert is downturned substantially at right angles to the body portion as at 16^c to the bottom of the container and bent along the bottom parallel to the body portion for a short distance as at 16^d and upturned again as at 16^e parallel to the downturned portion 16^c so as to provide a recess 17 to receive a toilet article such as a lip stick or the like indicated generally at 18. In the main body portion 16 of the insert is provided the central opening 19 and the body portion is depressed conically as at 16^b towards said opening so as to abut against the cosmetic 20 held in compartment 13 and shield the latter. This cosmetic may be a compact face powder or the like article which is dispensed by rubbing with a puff. The granules of the cosmetic that usually drop to the bottom of the container during use are kept out by means of the guard effect of the insert, and the bottom of the container is further shielded from dirt and other foreign matter that might otherwise drop thereinto; so that the insert serves both as a shield and to afford a neat receptacle for an additional toilet article.

It will thus be seen that there is provided a device in which the several objects of this invention are achieved and which is well adapted to meet the conditions of practical use.

As various possible embodiments might be made of the above invention and as various changes might be made in the embodiment above set forth it is to be understood that all matter herein set forth or shown in the accompanying drawings is to be interpreted as illustrative and not in a limiting sense.

Having thus described my invention I claim as new and desire to secure by Letters Patent:—

In a vanity case, a heart-shaped container, a hinged cover for said container, and a guard member disposed in and fitted to occupy the entire container, said guard member comprising a piece of sheet material having a circular opening therein and a portion

depressed from the normal upper surface 10 thereof, said portion extending along the side of the container, adjacent the hinged cover, the perimeter of said opening being centrally inscribed to occupy substantially the entire undepressed portion of said 15 member.

In testimony whereof I affix my signature.
CHARLES LIONEL MARCUS.
